UNITED STATES PATENT OFFICE

FREDRIC C. WEIR, OF CINCINNATI, OHIO.

SWITCH-BAR ATTACHMENT.

SPECIFICATION forming part of Letters Patent No. 374,100, dated November 29, 1887.

Application filed July 12, 1887. Serial No. 214,101. (No model.)

To all whom it may concern:

Be it known that I, FREDRIC C. WEIR, of Cincinnati, in the county of Hamilton and State of Ohio, have invented certain new and useful 5 Improvements in Switch-Bar Attachments, of which the following is a specification.

My invention relates to a novel construction of a switch-bar clamp and holder.

One of the objects of this invention is to 10 furnish, to a limited extent, flexibility in the switch-bars, so that they will move easily, and bring the switch-rail into position without being bent or sprung.

Another object of my invention is to employ 15 the bolts in a horizontal position which fastens the switch bar to its clamp, so that the nuts will be less liable to come off and the bolts drop out.

Another object of the invention is to provide 20 suitable means for clamping the switch-bar in such a way as to take up lost motion and to prevent rattling, producing a slightly-flexible but firm attachment of the switch-bar to the rail, all of which will be hereinafter set forth. To accomplish these results I employ the 25 devices illustrated in the accompanying drawings, making a part of this specification, in which—

Figure 1 is a sectional elevation of my improvement. Fig. 2 is an enlarged view of one 30 of the switch-bar clamps attached to the rail shown in sections. Fig. 3 is a side elevation of the clamps attached to the switch-bar. Fig. 4 is a section on line $x-x$, Fig. 2. Fig. 5 is a 35 section on line $y-y$, Fig. 3.

11 represent the main or whole rails; 22, the switch or movable rails; 3, the switch-bar. I have shown this bar in Fig. 1 with one end 40 adapted to be attached to a vertical switch-stand and the other end adapted to be attached to a horizontal switch-stand.

4 represents the switch-bar clamp and holder. The base of this is a plate pierced with holes to receive the fastening-bolts 5.

45 66 represent strengthening ribs cast onto the plate and projecting outward and downward and terminating in a bifurcated arm, a , which

forms the attaching switch-bar support, having the slot 7 adapted to receive the switch-bar, lugs or shoulders 8 on which the same rest, a 50 space, 9, between the shoulders 8, shoulders 10 at the top of opening 7, and the slot 11 between said shoulders 10.

The opening 7 is made flaring or beveling from the center outward, as shown in Fig. 5. 55 This accomplishes two offices. First, it allows the switch-bar to be clamped by the fork-arms a , which, owing to the slots 9 and 11, allow it to be sprung sufficiently to clamp the bar and yet allow it to spring sidewise in either direction. To accommodate itself to the end movement of the rail, caused by contraction and expansion, this construction also allows the switch-bar to be used vertically with the fastening-bolts 5 lying in horizontal position. The 65 construction here shown has the supporting-arms a projecting downward below the rails a sufficient distance, so that the switch-bar may be passed clear through under the rail, and is the preferred form of construction. 70

Having described my invention, what I claim is—

1. In combination with the switch-rails, the switch-bar-clamp holder attached to said rails, with the bifurcated arms a , forming openings 7, and the opening 9 between the supporting-shoulders 8, substantially as specified. 75

2. The switch-bar clamp and holder, composed of base 4 and the supporting-arms a , having an opening 7, the supporting-shoulders 80 8 and 10, and openings 9 and 11 between said shoulders, substantially as specified.

3. The switch-bar clamp composed of the base 4 and the arms a , with the faces of said arms beveled from the center outward, the 85 opening 9, and bolt 12, whereby the switch-bar 3 is securely clamped at the center of the support, substantially as specified.

In testimony whereof I have hereunto set my hand.

FREDRIC C. WEIR.
